(57) **CLAIM**

The ornamental design for a rocker cover for a vehicle, as shown and described.

DESCRIPTION

This application contains subject matter related to the following co-pending U.S. design patent application:

Application Ser. No. 29/760,351, filed herewith and entitled "rocker cover for a vehicle".

FIG. 1 is a right, front perspective view of a rocker cover for a vehicle according to the design;

FIG. 2 is a left, bottom perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.
